STOP HINGE FOR LUGGAGE CASES

Joseph H. Plotkin, Chicago, Ill., assignor to S. Dresner & Son, Inc., Chicago, Ill., a corporation of Illinois

Application April 2, 1938, Serial No. 199,543

2 Claims. (Cl. 16—191)

This invention is directed to a hinge construction for luggage cases, which combines stop features for limiting the opening of the case sections, and in particular the construction is one which is sufficiently compact to be practically concealed within the lining of the case, so that it will not protrude itself unduly, but will at the same time afford adequate means for holding the case sections in open position without the necessity for providing separately attached links or the like for such purpose.

Further objects and details will appear from a description of the invention in conjunction with the accompanying drawings, wherein—

Fig. 1 is a sectional view of a portion of a luggage case displaying one of the forms of the present invention;

Fig. 2 is a similar view showing the case sections in open relation;

Fig. 3 is a perspective detail of the slotted link plate;

Fig. 4 is a perspective detail of one of the hinge sections for pivoting the link plate;

Fig. 5 is a plan view of a somewhat different form of hinge construction, showing the hinge sections in the closed position;

Fig. 6 is a similar view showing the hinge sections in open position;

Fig. 7 is an edge elevation of the hinge sections in the closed position;

Fig. 8 is a similar view with the hinge sections in the open position; and

Figs. 9 and 10 are sectional elevations of the hinge sections in the closed and open positions respectively.

Referring first to the construction shown in Figures 1 to 4, the hinge of the present invention is applied to a luggage case comprising sections A and B, the former of which may be regarded as the bottom section and the latter the top section.

The hinge 11 comprises two sections each consisting of an inner face plate 12 and an edge flange 13, the latter flanges being of interfitting tubular form to receive a pintle 14. One of the hinge sections is provided with a headed stud 15 which coacts with an arcuate link plate 16 provided with a slot 17 adapted to ride upon the headed stud, which affords a stop for engaging the terminus of the slot when the case is opened as in Fig. 2.

The link is preferably stamped out of a flat plate to provide trunnions 18 which, as shown, are journaled within a pair of sleeve-like protuberant portions 19 formed at the angle of the compa-

nion hinge plate, which arrangement affords a convenient pivot for the end of the slotted link when the hinge plate is secured in position.

In order to protect the working parts from contact with the contents of the luggage case, a shield or guard 20 is secured to that one of the hinge plates which carries the headed stud 15 in position to overlie the stud and the major portion of the link when the case is closed. The arcuate slotted link will accommodate itself to the movement of the headed stud 15, and when the limit of movement is reached will serve to hold the case sections open.

In the form shown in Figures 5 to 10 inclusive, the hinge comprises a plate section 21 which is secured to the inner face of the rear wall of one of the case sections, and said section coacts with a slideable hinge section 22, the two sections being provided with interfitting sleeve portions 23 which are pivoted by a pintle 24. The slide plate section 22 is held in adjacent relation to a plate 25 which is secured to the inner face of the rear wall of the companion case section and is provided with inturned tongues 26 which engage the edges of the slide plate and afford limited sliding movement thereto.

The base plate 25 is provided with outstanding stop tongues 27 which register with slots 28 in the slide plate section 22, so that the latter will be afforded the limit of sliding movement indicated in Figures 5 and 6, which is necessary in order to permit the necessary clearance in swinging the hinge from the closed to the open position. It will be noted that in the closed position indicated in Fig. 7, the edges of the companion case sections stand in edge abutting relation and that the sections are of considerable thickness, while in Fig. 8, the edge of one of the sections overlaps the outer edge wall of the companion section, and the sliding movement provided must be sufficient to afford the necessary clearance to the case sections in the movement indicated.

However, in order to hold the edges of the case sections tightly together, as in Fig. 7 when the case is closed, it is necessary to provide a latching means which will now be described.

The base plate 25 is provided with an outstanding tongue 29 terminating in a flange 30 which coacts with a hooked finger 31 projecting forwardly from the plate 21. During the closing of the case sections, the hooked finger will ride over the flange 30 and engage the flange in the manner shown in Fig. 7, which holds the edges of the case sections in close abutment and prevents

the retraction which would otherwise be permitted by the limited movement of the slide plate 22. However, when the sections of the case are swung open on the hinges, the hooked finger will 5 free itself from the keeper flange 30, and this will allow the slide plate to be drawn outwardly by its hinge connection with the companion plate 21, thus allowing the freedom of movement necessary to permit the sections of the case to assume the position indicated in Fig. 8.

10 Ordinarily it will not be necessary to make the hooked finger 31 of spring material, since there will be sufficient looseness and freedom of movement to permit these parts to be released under pressure, but if more accurate fitting is desired, 15 the hooked latch finger 34 may be made of spring material, so as to yield in passing over the flange 30.

10 In use, with the sections of the case closed as in Fig. 7, the edges will stand in close abutment and will be locked against the creation of a gap by the engagement of the latch finger 31, but these parts will release under a swinging movement, and this permits the slide plate to be drawn out to the limit of its movement and until 25 the sections of the case have assumed the position shown in Fig. 8. In this position, the pressure of the hinge will be relieved by the contact of the edge of the open top section with the outer 30 marginal wall of the bottom section, and this in addition to the reinforcement afforded by the stop tongues 27 will prevent further opening of the parts, without, however, subjecting the hinges to undue strains in view of the reinforcement provided. This arrangement is extremely compact in that the operating parts all lie flatwise 35 against the rear walls of the case sections, with no protruding parts which extend outwardly to any material degree. The arrangement is one which may be readily covered and practically 40 concealed by the lining of the case, so that there will be no interference with the contents of the case.

45 In both constructions, compactness in arrangement has been secured to a marked degree, without, however, sacrificing the bracing action required in holding the open section of the case in upstanding relation, thereby dispensing with conspicuous links, braces, or the like, which are 50 commonly employed for holding the parts in open position. Furthermore, in both forms of construction, the operating parts are all made of stamped material of stiff and rugged construction, so that abundant strength can be secured 55 without the addition of extraneous braces.

55 Although the invention has been described with particularity as to detail, it is not the inten-

tion, unless otherwise indicated, to limit the construction to the forms here shown, since modifications therein may be made without departing from the spirit of the invention.

5 I claim:

1. A hinge for the two sections of a luggage case or the like comprising, companion hinge plates each having an inner plate portion adapted to be secured to the inner face of the rear wall of each said case sections, an angularly disposed flange portion extending from each inner plate portion adapted to embrace the end faces of said rear walls, a pintle pivotally uniting said flange portions at a point outwardly offset with respect to the plane of said inner plate portions, 10 one of said hinge plates being formed at the angle between its inner plate portion and flange portion with a sleeve-like protuberance, a slotted link plate having a trunnion journaled within said sleeve-like protuberance, said link plate being of a length to overlap the inner plate portion of the other hinge plate in all positions of said hinge plates, and a stop member outstanding from the inner plate portion of said other hinge plate for engaging the slot in said link 15 plate for limiting angular movement between the companion hinge plates.

2. A hinge for the two relatively swingable sections of a luggage case or the like comprising, companion hinge plates each having an inner 20 plate portion adapted to be secured to the inner face of the rear wall of each said case sections, an angularly disposed flange portion extending from each inner plate portion adapted to embrace the end faces of said rear walls, one of said flange portions being bifurcated, a pintle pivotally uniting said flange portions at a point outwardly offset with respect to the plane of said inner plate portions, one of said hinge plates being formed at the angle between its inner plate 25 portion and bifurcated flange portions with aligned sleeve-like protuberances, a longitudinally curved and slotted link plate having oppositely extending trunnions at its inner end journaled within the opposed ends of said protuberances, 30 said link plate being of a width to swing freely between said bifurcated flange portions and of a length to overlap and slide upon the inner plate portion of the other hinge plate in all positions of said hinge plates, and a stop in the form of a headed stud outstanding from the inner plate portion of said other hinge plate and slidably interlocked with said slotted link plate for limiting angular movement between the companion 35 hinge plates.

JOSEPH H. PLOTKIN.
